UNITED STATES PATENT OFFICE

THOMAS A. MILMORE, OF BROOKLYN, NEW YORK

RAPID REVOLVER LOADER

Refiling of abandoned application Serial No. 395,235, filed September 26, 1929. This application filed December 14, 1931. Serial No. 581,030.

My invention relates to devices for simultaneously charging all the chambers in the cylinder of a revolver. It has for its main object to provide a device which makes it possible to completely load or reload a revolver in a space of time no longer than that required for inserting a single cartridge, and to do so without any previous practise or skill. Another object is to provide a device which will not be bulky but which will hardly occupy any more space than that which the same number of individual cartridges would occupy. A further object is to provide a device of simple construction and so inexpensive to manufacture that it may be discarded after its initial use.

While I am aware that other devices of this kind have been invented, my invention contains features which markedly differentiate it and which add greatly to its utility.

These and various other objects and advantages will be readily understood from the following description and from the accompanying drawings of preferred embodiments, but it will be noted that various modifications may be made without departing from the scope of the invention. In the drawings:

Fig. 1 is a side elevation of the loader, shown straightened out;

Fig. 2 a plain view, showing it in its normal position;

Fig. 3 is a side elevation of the case in which it is carried;

Fig. 4 a sectional, top view of the case, taken on line 4-4, Fig. 3;

Fig. 5 an end view of the case;

Fig. 6 a plan view of the loader, shown depositing the cartridges in the cylinder of a revolver;

Fig. 7 a side elevation of a modification of the loader, shown straightened out;

Fig. 8 a plan view of same, shown in its normal position;

Fig. 9 another plan view, shown straightened out;

Fig. 10 a perspective view, showing how the loader is used;

Fig. 11 is a side elevation of another modification of the loader, shown straightened out;

Fig. 12 a plan view of same;

Fig. 13 another plan view, showing the loader in its normal position; and

Fig. 14 still another plan view, showing the loader depositing cartridges in the cylinder of a revolver.

55

Referring first to Figs. 1 to 6, the device consists of a flat spring 10 which is provided with a finger grip 11 and of a plurality of cartridge clips 12 which are welded, soldered or otherwise suitably secured to the spring. 60 The clips extend only a sufficient distance around the cartridges 13 to hold these securely and therefore have a rather large opening between their ends. The cartridges are prevented from being displaced longitudinally 65 by the cartridge flanges 14 which fit between the top edge of the spring 10 and detents 15. These are formed on the clips and offset to accommodate the flanges.

In Fig. 1 the spring 10 is shown straightened out. Its normal position is that shown in Fig. 2. The spring normally forms a hoop; the end 16 abutting against the first clip. When in this position, the clips, and consequently the cartridges contained therein, align with the chambers in the cylinder of the revolver, the number of clips being equal to the number of chambers.

As it would be inconvenient and cumbersome to carry the device in its normal position, a case 17 is provided in which it is inserted and carried in the straight or open position. This case, which may either be made of leather of sufficient stiffness to hold the loader open, or, if made of lighter material, 80 may be provided with a stiffening member 18, can be carried on a belt by inserting this through the straps 19. It can, of course, be made to conform to the contour of the body 85 of the wearer. In place of the straps 19, 90 other suitable means may be employed so that the case may be carried and secured in a hip pocket, for example. The case is provided with a flap 20 and a snap fastener 21.

It will readily be understood that when 95 the loader is withdrawn from the case, it instantly assumes the shape shown in Fig. 2. If the lower ends of the cartridges are now inserted in the chambers in the cylinder 22 until the spring rests on the cylinder and the 100

finger grip pulled in the direction indicated by the arrow in Fig. 6, the cartridges will be released from the clips and drop into their places in the cylinder. This action is made possible by the comparatively large openings between the ends of the clips and by the positions of the clips on the spring, which is clearly shown in the drawings. While the cartridges are released the cylinder rotates in the direction of the curved arrow. As shown in Fig. 6, the cartridges marked A have been released from their clips, while the remaining cartridges are still engaged in their respective clips.

By substituting a plain ring 32 for the finger grip shown and by making the clips of untempered material, the device can be manufactured so cheaply that it can be discarded after being used but once. This is quite important in many cases.

A modification, the principle of which is the same as in the device just described but which is constructed differently, is shown in Figs. 7 to 10. In this case a plurality of spring-actuated links 23 are substituted for the spring 10. The links are pivoted at 24 and each is provided with a downwardly extending cartridge-clip 25. Each link is offset and formed with two stops 26 and 27 which abut against the offset 28 of the adjoining link when the device is in the positions shown in Figs. 8 and 9. The first link is provided with a finger grip 29. Tension springs 30 normally hold the device in position as shown in Fig. 8.

This device is also carried in a case similar to the case 17. The cartridges are deposited in the cylinder just as described in the first case. Fig. 10 shows the complete revolver and plainly illustrates how the device is used. The springs shown in this device may be omitted. A toss of the wrist will cause the links to assume the position shown in Fig. 8.

The modification shown in Figs. 12 to 14 operates similarly to the devices described, but is constructed somewhat differently. It consists of a plurality of links 33 hinged together by spring-actuated hinges 34. Each link has a detent 35 which completely covers the head of the cartridge 13. These detents are so constructed that they abut against each other when the device is in the normal position shown in Fig. 13. The handle is shown at 36 and the cartridge clips at 37.

Having described my invention and its operation, what I claim as new and wish to protect by Letters Patent is:

1. In a device of the class described, a spring member normally forming a hoop but having its ends free, and a plurality of cartridge clips secured in spaced relation on said spring member, the cartridge clips being disengageable from the cartridges inserted therein by a tangential pull on one end of the spring member.

2. In a device of the class described, a spring member normally forming a hoop but having its ends free, a plurality of cartridge clips secured in spaced relation on said spring member, and a detent formed on each of said clips for preventing displacement of the cartridges inserted therein. 70

3. In a device of the class described, a spring member normally forming a hoop but having its ends free, a plurality of cartridge clips secured in spaced relation on said spring member, and a finger grip secured to one end of the said member, the cartridge clips being disengageable from the cartridges inserted therein by a tangential pull on the finger grip. 80

4. In a device of the class described, a spring member normally forming a hoop but having its ends free, a plurality of cartridge clips secured in spaced relation on said spring member, a handle secured to one end of the spring member, the spring member being straightenable so that the device may be contained in a substantially straight casing and the cartridge clips being disengageable from the cartridges inserted therein by a tangential 90 pull on the handle. 85

5. In a device of the class described, a plurality of links, a cartridge clip secured to each of said links, a handle member formed on one of the outer links, and means associated with said links for limiting their movements from that of a substantially straight position to that of a circular position, and the cartridge clips being disengageable from the cartridges inserted therein by a tangential 100 pull on the handle member. 95

6. In a device of the class described, a plurality of spring-actuated links, a cartridge clip secured to each of said links, a finger grip formed on one of said links, the tendency of the spring action being to form the links into a hoop, the cartridge clips being disengageable from the cartridges inserted therein by a tangential pull on the finger grip. 110

7. In a device of the class described, a plurality of spring-actuated links, a cartridge clip formed on each of said links, a handle member secured on one of said links, means associated with all of said links for limiting their movements from that of a substantially straight position to that of a circular position, and the spring action upon the links being such as to normally hold them in the last mentioned position, and the cartridge clips being disengageable from the cartridges inserted therein by a tangential pull on the handle member. 115

8. In a device of the class described, a plurality of spring-actuated links, a cartridge clip attached to each of said links, a handle member attached to one of said links, means associated with all of said links for limiting their movements from that of a substantially straight position to that of a cir- 125 130

cular position, the spring action upon the links being such as to cause them to assume the last mentioned position when in its straight position, the device being containable in a substantially straight casing and the cartridge clips being disengageable from the cartridges inserted therein by a tangential pull on the handle member.
